UNITED STATES PATENT OFFICE.

JEPPE JÖRGEN A. SÖRENSEN, OF ERIE, PENNSYLVANIA.

MANGLE.

SPECIFICATION forming part of Letters Patent No. 314,269, dated March 24, 1885.

Application filed September 7, 1883. (No model.)

To all whom it may concern:

Be it known that I, JEPPE JÖRGEN A. SÖRENSEN, a citizen of Sweden, residing at Erie, in the county of Erie and State of Pennsylvania, have invented certain new and useful Improvements in Mangles; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to improvements in clothes-mangles and portable frames therefor.

The objects of my invention will appear hereinafter in the specification and claim.

In the accompanying drawings, illustrating the features of my improvements, Figure 1 is a perspective view of my entire machine. Fig. 2 is a vertical section of my machine through the line *x x* in Fig. 1. Fig. 3 is a side elevation of my machine when folded up. Fig. 4 shows a section of my machine 25 with the cloth to be mangled being rolled around the middle roller.

Similar letters refer to similar parts throughout the several views.

The frame-work of my device consists of 30 the base *K K*, having cross-piece *k k* and *j*, to which are hinged the standards *E E* at *J J'*. The standards *E E* have a cross-piece, *F*, connecting their tops together. The table *D* is also hinged to the standards *E E* at *J J*, 35 the outer end of the table *D* being supported by legs *I I*, hinged to the table at *J J'*, and the lower ends of the legs *I I* rest upon the side pieces of the base *K K*, being held in place by dowel-pins *t t*, entering holes *t' t'* 40 in the ends thereof, when the machine is ready for use. The legs *I I* are also connected together by a cross-piece, *i*.

The rollers *A B C* are mounted one above the other in grooves *e e*, cut in the standards 45 *E E* of the frame, as shown in Fig. 1. The lower roller, *C*, is so placed that its surface is slightly above the top of the table *D*. This roller *C* has attached to its journal *c* a crank, *c'*, by which it is turned. The roller *B* 50 rests upon the roller *C*, and has attached there-

to a double web, *u u'*, and moves freely up and down on its journals *b b* in the grooves *e e*. The roller *A* rests upon the roller *B* and moves up and down in the grooves *e e* on its journals *a a*. Upon the journals *a a* rest pressure-blocks *h h*, and bearing upon these pressure-blocks *h h* are spiral springs *H H*, which work in the grooves *e e*. Upon the tops of the springs *H H* rests a movable cross-piece, *G*, under the cross-piece *F* of the frame, the thumb-screws *F F* passing through *F* and resting upon the movable piece *G*, by means of which thumb-screws *F F* the pressure upon the springs *H H* may be increased or decreased at pleasure.

In operation the crank *c'* is turned so as to bring the web *u u'* around so as to unwind it from the roller *B*, to which it is attached, so that it will lie upon the table *D*, as shown in Fig. 2. The cloth to be mangled is then laid out upon the table so that one end of it will lie upon or between the parts of the web *u u'*. Then by turning the crank *c'* the cloth to be mangled is wound around the roller *B*, as shown in Fig. 4, and at the same time brought 75 in contact with the pressure of the rollers *A* and *C*. After subjecting the cloth to a few turns of the rollers, the motion of the rollers is reversed, by turning the crank *c'* backward, and the goods removed from the rollers, this process being repeated with each piece of goods 80 to be mangled.

In folding up my machine, as shown in Fig. 3, the hooks *M* are detached and the table *D* folded against the upper portion of the standards *E E*, and the base of the frame *K* is also folded up, as shown, the dowel-pins *t* passing into holes *k' k'* in the ends of the side pieces, *K K*. The hooks *L* being then inserted into the staples hold the frame folded together, as shown in Fig. 3.

I am aware that mangles have heretofore been constructed with three rollers, and therefore do not claim three rollers acting together in a mangle as new.

What I do claim, and desire to secure by Letters Patent of the United States, is—

In a clothes-mangle, the base-frame *K K*, provided with holes *k' k'* and *t' t'*, the standards *E E*, hinged to the center thereof and sup-

porting the compression-rollers, in combination with the table D, hinged to the standards E E in front of the compression-rollers, legs I I, hinged to the outer edge of the table, where-
5 by the said parts may be placed in operative position or the table and base folded up against the standards E E, and hooks and staples for holding the parts in the desired

positions, substantially as and for the purpose set forth.

In testimony whereof I affix my signature in presence of two witnesses.

JEPPE JÖRGEN A. SÖRENSEN.
